UNITED STATES PATENT OFFICE.

FRED G. NORMAN, OF DAVENPORT, IOWA.

PAPER-HOLDER OR JOGGING-BOARD FOR PRINTING-PRESSES.

1,246,986.

Specification of Letters Patent. Patented Nov. 20, 1917.

Application filed April 30, 1917. Serial No. 165,566.

To all whom it may concern:

Be it known that I, FRED G. NORMAN, a citizen of the United States, residing at Davenport, in the county of Scott, State of Iowa, have invented a new and useful Paper-Holder or Jogging-Board for Printing-Presses; and I do hereby declare the following to be a full, clear, and exact description of the invention, such as will enable others skilled in the art to which it appertains to make and use the same.

This invention relates to a paper holder or support for use in connection with printing presses for holding the paper before and after printing, and in trade or commercial fields, this type of device is entitled "jogging-board," hence, this term will be employed hereinafter in this specification.

One of the objects of the invention is to provide a jogging board provided with means to be engaged by suitable projections on a partition, in order to hold the partition in different positions, whereby the paper, before and after printing, may be held even.

In practical fields, the details of construction may necessitate alterations falling within the scope of what is claimed.

The invention comprises further features and combination of parts, as hereinafter set forth, shown in the drawings and claimed.

In the drawings:—

Figure 1 is a view in perspective of the jogging-board, constructed in compliance with the invention.

Fig. 2 is a transverse sectional view on line 2—2 of Fig. 1.

Fig. 3 is a perspective view, showing a slightly different form of jogging-board, as applied to a portion of a printing press, and illustrating in connection therewith the usual auxiliary paper holder or board.

Referring more especially to the drawings, 1 designates the usual or conventional jogging-board of a printing press and 2 is a portion of the platen of the press. This jogging-board comprises a horizontal portion 3 and a vertical part or flange 4, which is adjacent the platen. Secured upon the board 1, by means of screws 5, is the improved jogging board or plate 6, which comprises the horizontal part 7 (which corresponds with and engages flat against the part 3 of the board 1) and the vertical portion or flange 8 (which corresponds with and engages the flange 4). The horizontal portion 7 of the auxiliary jogging board 6

is provided with one or more rows of rectangular openings 9, extending transversely of the board and arranged at spaced intervals. The upper edge portion of the flange 8 of the auxiliary jogging board is provided with notches 10 arranged at spaced intervals corresponding to the intervals of the openings 9. A suitable partition or plate 11 (which may be any suitable shape or configuration) is provided. The upper part of the forward edge of this partition is provided with a lug 12, which may engage any one of the notches 10, to assist in holding the partition in position, as shown in Figs. 1 and 3. The lower edge of the partition is provided with a pair of lugs 13, which are designed to engage any two opposite openings 9 (which are aligned with the notch engaged by the lug 12) in the horizontal portion 7 of the auxiliary jogging board, to further assist in holding the partition in place. It is to be observed that by this partition, the jogging-board is divided into two compartments or spaces 14 and 15, which may vary in width, according to the adjustment of the partition. The paper to be printed may be placed in either one of the compartments or spaces, according to the one that may be considered most convenient to the pressman, and as the sheets are removed from the platen of the press, subsequently to receiving the printing impressions, they may be placed in the compartment or space. The sheets of paper before and after printing are arranged in the spaces so as to fit snugly into the corners adjacent the partition and the flange 8, thereby holding the sheets of paper with their exposed edges even or flush. By virtue of the openings 9 and the notches 10, the partition may be adjusted to vary the spaces 14 and 15, whereby the sheets of paper of different sizes may be accommodated. In Fig. 3, the auxiliary jogging-board is applied to a slightly different form of press, which is provided with a second auxiliary paper holder or table 16, which is mounted on a standard 17 rising upwardly from and secured to the jogging board 1. In order that the jogging board 6 in Fig. 1 may be applied to the press in Fig. 3, said board 6 is provided with an annular cut-away portion or recess 18 to accommodate the standard 17.

The invention having been set forth, what is claimed as new and useful, is:—

In combination with a printing press

jogging-board, an auxiliary jogging-board having a horizontal portion and a vertical forward flange, whereby said auxiliary board may conform to and fit the jogging board of the printing press, means to secure the auxiliary board to the first jogging-board, the horizontal portion of the auxiliary board having two rows of openings, the openings of each row being at spaced intervals, the upper edge portion of the forward flange of the auxiliary board, having spaced notches aligned with said openings, and a partition having its forward end edge and its bottom edge provided with lugs to

respectively engage said notches and said openings, whereby the partition may be adjusted for varying the spaces on opposite sides thereof, one end of the auxiliary jogging-board having an angular cut-away portion to accommodate an upright standard on the first jogging-board.

In testimony whereof I have signed my name to this specification in the presence of two subscribing witnesses.

FRED G. NORMAN.
